UNITED STATES PATENT OFFICE.

JOHN MUSTO, OF WATERBURY, CONNECTICUT.

SPRING HEEL.

Application filed August 4, 1924. Serial No. 729,963.

To all whom it may concern:

Be it known that I, JOHN MUSTO, a citizen of the United States, and a resident of Waterbury, county of New Haven, and State 5 of Connecticut, have invented certain new and useful Improvements in Spring Heels, of which the following is a specification.

This invention relates to spring heels for boots and shoes, and more particularly to 10 a spring heel having a plurality of springs and in which the positions of the springs may be adjusted as may be desired according to the condition of the foot.

A further object is to provide a spring 15 heel of the above nature in which the tread member may easily be removed and interchanged with a similar tread member from the other shoe of a pair.

A further object of the invention is to 20 provide a device of the above nature which will be simple in construction, inexpensive to manufacture, ornamental in appearance, easy to install and manipulate, and very efficient and durable in use.

25 With these and other objects in view, there have been illustrated on the accompanying drawings two forms in which the invention may be conveniently embodied in practice.

30 Fig. 1 represents a fragmentary elevation of the rear portion of a shoe, showing in section the first form of spring heel attached thereto.

Fig. 2 is a bottom view of the same, with 35 the lower portion of the spring heel removed for greater clearness.

Fig. 3 is a view similar to Fig. 1 showing the second form of spring heel attached to a shoe.

40 Fig. 4 is a perspective view of the upper hollow shell of the spring heel shown in Fig. 3.

Fig. 5 is a perspective view of the cover plate adapted to be used with the shell 45 shown in Fig. 4.

Referring now to the drawings in which like reference numerals denote corresponding parts throughout the several views, the numeral 10 indicates a hollow shell having 50 a flat upper base 11 adapted to be held in contact with a sole 12 of a shoe 13 by means of screws 14 passing through apertures 15 in said base.

The shell 10 is provided with a flange 16 55 extending downwardly from the edge of the base 11, and the sides 18 and rear 19 of

said flange being bent inwardly at 17^a for a short distance parallel to the base 11 to form a shelf. The forward portion 17 of the flange 16 is of slightly less height than 60 the sides 18 and rear 19 thereof, so as to permit a plate 20 to be slid into the shelf 17^a, as shown in Fig. 1.

In order to permit the removal of the plate 20, a curved slot 20^a is formed in the 65 forward portion 17 of the flange 16, whereby a screw driver or other tool may easily be inserted therein to force the plate 20 downward under the forward portion 17.

The plate 20 is provided with a series of 70 apertures 21 for receiving the upper ends of lugs 22, said lugs 22 having enlarged lower heads 23 adapted to be embedded in suitable sockets in a rubber heel or tread member 24.

Secured to the under side of the base 11 are a series of adjustable arms 25—four in number in this instance—said arms having apertures at one end surrounding the screws 14, previously mentioned. The arms 25 are 75 provided at their free ends with downwardly depending plugs 26, each of said plugs being surrounded by a spiral spring 27 of any suitable size and material, as clearly shown in Figs. 1 and 2.

In operation, when it is desired to change the position of one of the spring-holding arms 25, it will only be necessary to remove the plate 20 and tread portion 24 in the manner described above, and to loosen the 90 proper one of the screws 14. The arm 25 may then be rotated to the position desired, after which the screw 14 will be tightened and the plate 20 and the heel 24 may be moved back into their normal position as 95 shown in Fig. 1.

In the modified form of the invention shown in Figs. 3-5, the flange 16 of the shell 10^a is provided on its sides 18 and 19 with a continuous semi-circular bead 28. This 100 form of spring heel has a plate 20^b shaped to slide within the shell and on its sides and rear has an upstanding rib 29 adapted to fit within the bead 28 when the plate has been slid into position.

105 By means of this construction, it will be seen that it will be impossible for the plates 20 and 20^b of either form to accidentally come out of the shells 10 and 10^a, and said plates 110 can only be removed by the use of the screw driver or other suitable tool inserted in the slot 20^a as described above.

The springs 27 in the second illustrated form of the invention are not adjustable, as in the first form, but are fixed in position by a series of screw plugs 30 upon which they are mounted. The upper ends of the screw plugs are threaded and adapted to pass through the base of the shell and into the sole of the shoe. The heel tread 31 of the second form of the invention has a series of 10 open sockets 32 extending from the bottom of the tread part way toward the top thereof, and the heel tread 31 is adapted to be secured to the plate by a series of headed screws 33 seated in said open sockets 32 and 15 having their ends threaded to engage in threaded holes 34 in the plate 20.

It will thus be seen that with the second form of the invention, not only may the plates with their attached treads be interchanged from one shoe to the other, but the tread of each heel may be removed and replaced by a new one whenever desired without the use of cement or other type of adhesive material.

25 It will be understood that the present invention is not limited to the use of spiral springs, but other types of springs may be employed if desired. Also different shapes of flanges and beads may be employed instead of the forms shown.

Moreover, instead of a sliding plate, as illustrated, a plate may be employed which will be "snapped" into position if desired, by pushing it transversely into the shell.

30 35 While there have been disclosed in this specification two forms in which the invention may be embodied, it is to be understood that these forms are shown for the purpose

of illustration only, and that the invention is not to be limited to the specific disclosures 40 but may be modified and embodied in various other forms without departing from its spirit. In short, the invention includes all the modifications and embodiments coming within the scope of the following claims. 45

Having thus fully described the invention, what is claimed as new, and for which it is desired to secure Letters Patent, is:

1. In a spring heel, a hollow shell adapted to be attached to the rear of the sole of a shoe, a plate releasably closing said shell, said plate having a heel tread secured thereto, a spring located in said shell and engaging said plate, and adjustable means for holding said spring in various positions 55 within said shell.

2. In a spring heel, a hollow shell adapted to be attached to the rear of the sole of a shoe, a plate releasably closing said shell, an arm pivoted to said shell, a spring seated on said arm, and means for holding said arm and spring in different adjusted positions 60 within said shell.

3. In a spring heel, a hollow shell, means for holding said shell to the rear of the sole 65 of a shoe, a plate releasably closing said shell, said plate having a heel tread secured thereto, a plurality of springs secured to said shell and adjustable relative thereto, and means for holding said springs in any 70 adjusted positions, the means for holding said shell to said sole also serving to hold said spring holding means to said shell.

In testimony whereof, I have affixed my signature to this specification.

JOHN MUSTO.
